JOHNSON & CRANE.

Heating Stove.

No. 12,758.

Patented April 24, 1855.

UNITED STATES PATENT OFFICE.

J. JOHNSON AND J. E. CRANE, OF LOWELL, MASSACHUSETTS.

STOVE, &c.

Specification of Letters Patent No. 12,758, dated April 24, 1855.

To all whom it may concern:

Be it known that we, JONATHAN JOHNSON and JOHN E. CRANE, of Lowell, in the county of Middlesex and State of Massachusetts, 5 have invented certain new and useful Improvements in Stoves and other Heating Apparatuses; and we do hereby declare that the following is a full, clear, and exact description of the same, reference being had to the 10 annexed drawings, making a part of this specification, in which—

Figure 1, is a plan or top view of a stove constructed according to our improved mode. Fig. 2, is a vertical section of ditto, the plane 15 of section being through the center. Fig. 3, is an elevation of ditto. Fig. 4, is a section of the cold air passage, valve, evaporator, and a portion of the air heating passage, the plane of section being at right angles with the plane of section of Fig. 2.

Similar letters of reference indicate corresponding parts in the several figures.

The nature of our invention consists, 1st, in placing a valve between the cold air and 20 air heating passages for the purpose as will be hereafter shown.

Our invention consists in the employment of a valve in combination with a bridge arranged as will be hereafter fully shown and 25 described.

To enable others skilled in the art to fully understand and construct our invention we will proceed to describe it.

A represents the outer casing of a stove 30 similar to those in use.

B is the fire grate.

C is the ash pit.

D is the hearth and E are legs secured to the hearth to support the stove.

40 Underneath the hearth D there is a drawer which is supplied with a suitable quantity of water, the drawer being in fact a water tank, see G, Figs. 2 3 and 4, and at the upper part of the back end of this tank a pipe F 45 is attached, said pipe communicating with the tank G. The pipe F is intended to convey cold air from the outside of the building or other place to the inside of the water tank, and said pipe may be placed beneath the 50 floor, or be arranged in any convenient way that will answer the purpose.

At the end of this pipe where it enters the tank G, there is placed a valve H which opens inward, the upper edge of the valve 55 having a joint or hinge attachment, see Fig.

4. Within the tank G and at a short distance from the valve H there is placed a bridge I which is somewhat inclined, said bridge extending the whole length of the valve. The tank G may be constructed with a double 60 bottom leaving a space K between as shown in Figs. 2 and 4.

L is an internal air heating passage extending upward from the water tank G beneath the hearth D, through the hearth, the 65 ash pit C, fire grate B, and through the body of the stove said passage L communicating with the external air at the top of the stove. The fire chamber it will be seen in consequence of the passage L is of annular form, 70 and may be supplied with fuel through openings M at the top, said openings being closed or exposed by rotating a plate O which is also provided with openings corresponding with the openings M. Or instead of the 75 above the usual fire door may be employed.

R represents the smoke pipe or the flanch on which the smoke pipe is fitted.

The cold air passes through the pipe F into the tank G, said air opening the valve 80 H, as indicated by the arrow in Fig. 4. The air is thereby moistened for the water in the tank is warmed by the heat from the stove and is gradually evaporating and consequently moistens the air. The air passes up 85 the central passage L and becomes thoroughly heated as it passes out at its top. Now in case of a counter current of air passing down the passage L the valve H will be closed thereby and the counter current will 90 be prevented from passing through the cold air pipe F, and the bridge I prevents the air from getting under the valve and forcing it open, by means of this bridge the counter current must act upon the valve so as to 95 close it.

The counter currents are extremely dangerous in using ordinary air heating furnaces, and they frequently occur owing to the low temperature of the air in the room 100 caused frequently by the opening of the doors and windows. The counter currents throw or carry heated air down into the cold air passage and the heated air often ignites wood work below and fires the building. Our invention prevents any danger of this 105 kind. The water tank also will receive any cinders or scales that may fall from the inner side of the passage L, and thus danger resulting from that cause is prevented.

We do not claim the central air heating passage L separately for that has been previously used, but

What we do claim as new and desire to secure by Letters Patent is—

We claim the employment of the valve H in combination with the bridge J, arranged

in the manner described, for the purpose specified.

JONATHAN JOHNSON.
JOHN E. CRANE.
